UNITED STATES PATENT OFFICE

2,467,316

PSYCHROMETER

Joseph Kahl, New York, N. Y.

Application July 5, 1945, Serial No. 603,384

11 Claims. (Cl. 73—338)

1

My invention relates to improvements in psychrometers and it consists in the novel features which are hereinafter described.

One of the objects of my invention is to provide a psychrometer having a horizontal air duct for the bulbs of the thermometer tubes to extend thereinto with a motor driven fan for circulating air through the duct and a means for employing the circulated air for cooling the motor and the electrical auxiliaries of the same, whereby to reduce or eliminate radiation of heat from the motor and its auxiliaries to the said thermometer bulbs.

Another object is to provide a housing, having therein openings, for enclosing the said air duct and the said fan, motor and its auxiliaries, whereby the circulated air after passing through the duct and fan casing is exhausted from the housing through the said openings therein, thereby cooling the said motor and auxiliaries.

A further object is to have the said air duct heat insulated on the outer surface thereof, whereby still further to reduce the transmission of heat therethrough by radiation from the said motor and auxiliaries.

A still other object is to provide the bulbs and lower ends of the thermometer tubes of the psychrometer with end tapered bushings encompassing the same, the tapered ends of the bushings to fit bevelled seats in the top of the air duct; the taper serves to make the openings in the top of the air duct coaxial with the openings in the top plate of the housing.

Another object is to have the said bushings heat insulated on the inner surface thereof, whereby to reduce radiation of heat from and through the said bushings to the lower ends of the thermometer tubes.

A further object of my invention is to provide on the psychrometer a means for supporting the upper ends of the thermometer tubes and a means for adjusting the vertical position of the said tubes.

A still other object is to provide on said housing radiation shields to serve also as a standard for mounting the said supporting means thereon and means on said shields for excluding light from the sides of the thermometer tubes, whereby to make the markings on the said tubes more conspicuous.

Another object of my invention is to have the said air duct encompassed by another air duct parallel thereto and having the walls of the two ducts spaced from each other, air being circulated through both ducts, whereby still fur-

2

ther to reduce or eliminate radiation of heat from the said motor and electrical auxiliaries to the bulbs of the thermometer tubes.

5 A further object is to provide suitable frames on said housing for holding the ends of each of said inner and outer ducts in position.

A still other object is to have the said outer air duct heat insulated on the exterior surface thereof, whereby to reduce the radiation from 10 the said motor and auxiliaries which may pass therethrough.

Another object is to provide the said housing with a partition of heat insulating material and to locate the fan with the motor and its auxiliaries in the compartment on one side of the partition in said housing and the ducts in the compartment on the other side thereof in communication with the casing of the fan through an opening in the said partition, whereby still further to prevent radiation of heat from the motor 20 and its auxiliaries to the bulbs of the thermometer tubes.

A further object is to place heat insulating material between the rear side of the flanges of 25 the frame which holds the outer end of the air duct and the part of the front of the housing to which the said frame is connected, whereby to prevent any conduction or radiation of heat from the housing to the air duct through the 30 said frame.

Other objects and advantages will hereinafter appear.

I attain these objects by the psychrometer, two forms of which are illustrated in the accompanying drawings or by any mechanical equivalents or obvious modifications of the same.

In the drawings—

Fig. 1 is a front elevation of one form of my improved psychrometer.

40 Fig. 2 is a horizontal section on the line 2—2—2—2 of Fig. 1.

Fig. 3 is a sectional plan view on the line 3—3 of Fig. 1 and also on the line 3—3 of Fig. 8, looking in the direction of the arrows, and drawn to 45 a larger scale than Figs. 1 and 2.

Fig. 4 is a vertical section on the line 4—4 of Fig. 3 drawn to a larger scale than Fig. 3 and referring to the form of my psychrometer as shown in Figs. 1 and 2.

50 Fig. 5 is a vertical section on the line 5—5—5—5 of Fig. 2, drawn to the same scale as Figs. 1 and 2.

Fig. 6 is a horizontal section on the line 6—6 of Fig. 8 referring to another form of my psychrometer.

Fig. 7 is a fragmentary front view in vertical section on the line 7—7 of Fig. 6.

Fig. 8 is a fragmentary vertical section on the line 8—8—8 of Fig. 6; and Fig. 9 is a fragmentary view in vertical section on the line 9—9 of Fig. 6, showing some parts in elevation.

Similar numerals refer to similar parts throughout the several views.

In the form of my psychrometer which is shown in Figs. 1, 2, 4 and 5, 11 designates a housing for enclosing therein sundry parts of the psychrometer, which are hereinafter described, and is shown as having thereon a cylindrical wall 12, a bottom plate 13 and a top plate 14; the wall 12 is shown as having therein openings 15.

The plates 13 and 14 and wall 12 are secured together by means of relatively long bolts 16 and nuts 17. The bolts 16, by reason of their length, are capable of yielding laterally so that when a sufficient force is applied thereto they deflect laterally and thereby the plate 14 may be adjusted relative to the remaining portion of the housing.

A duct 18 which is shown in Fig. 5 as rectangular in cross-section extends at the front end thereof through an opening in the wall 12 and a frame 19 which is secured to the wall 12 with a strip of heat insulating material 20 placed therebetween.

The duct 18 is shown in Fig. 5 as covered by a coat of heat insulating material 21 and is shown in Fig. 2 as having in the top side thereof two bevelled openings 22 for bushings 49 to rest thereon and for the bulbs 23 at the lower ends of the thermometer tubes 24 to pass therethrough and through the bushings 49 which are herein-after more fully described.

The rear end of the duct 18 extends into a fan casing 25 with which it communicates; the casing 25 encloses a fan 26 and discharges into the housing 11.

The fan 26 is connected by means of a shaft 27 to an electric motor 28 which is diagrammatically shown in Fig. 2.

The motor 28 is preferably of the D. C. variety, and the current may be supplied to it either by batteries which are not shown in the drawings or from a transformer 29 and a stack of rectifier plates 30 after an A. C. current is taken from a power line at a higher voltage and reduced by the transformer 29 to a required lower voltage and changed by the rectifier plates 30 to a D. C. current.

Sundry electrical switches and conduits which may be employed are omitted from the drawings.

Air is drawn by the fan 26 from the atmosphere at the front of the housing 11 through the duct 18 and fan casing 25 and passed into the interior of the housing 11 where it contacts with the motor 28, the transformer 29, rectifier plates 30 and the sundry other electrical auxiliaries which are not shown, and is then exhausted through the openings 15 in the wall 12 into the atmosphere outside of the wall 12 of the housing 11.

The motor and electrical auxiliaries including the transformer and rectifier discs are thereby being cooled and kept from being overheated, thereby reducing or eliminating radiation of heat from the said motor and auxiliaries to the bulbs 23.

One of the bulbs 23 is the dry bulb and the other is the wet bulb of the psychrometer; a baffle plate or partition 31 is shown as placed in the duct 18 to separate the air around each of the said bulbs.

The wicking which is employed to keep the wet bulb moist is omitted in the drawings.

A pair of radiation shields 32 are shown as mounted on the top plate 14 of the housing 11 and secured thereto by means of a curved strip 33—33a which is angular in cross-section and has its horizontal flange 33 secured to the plate 14 by means of bolts 34 and its vertical flange 33a to the lower end of each of the shields 32 by means of rivets 35.

The shields 32 have therein openings 36 for the admission of light therethrough, and serve as a standard for supporting thereon the upper ends 37 of the thermometer tubes 24 by means of a mushroom shaped top 38 on each of said ends 37 which is supported by an exteriorly threaded bushing 39 which is shown in engagement with an interiorly threaded opening 40 in the horizontal flange 41 of a curved strip 42 which is similar to the strip 33 and positioned symmetrically thereto. The mushroom 38 of each tube 24 rests on the upper end of each bushing 39. The thread in the opening 40 may be omitted if desired.

The vertical flange 43 of the strip 42 is secured to the upper end of each of the shields 32.

Each of the bushings 39 extends above the flange 41 and the thread thereon is in engagement with an interiorly threaded cap 44, which has its lower end resting on the flange 41 of the strip 42. The upper end of the cap 44 may be disposed to contact with the upper flange 45 of a Z-shaped member 46, the lower flange 47 of which is shown as secured to the flange 41 of the strip 42 by means of a screw 48. Each of the caps 44 is thereby adapted to act as a feed nut for the bushing 39 with the tube 24 which is supported thereby when the thread is omitted in the opening 40 of the flange 41.

When the thread is retained in the openings 40, the bushings 39 may be rotated by means of a suitable wrench to raise or lower the tubes 24; the caps 44 may then rotate with the bushings 39 and will serve only as covers for the upper ends of the tubes 24 with the bushings 39.

One of the Z members 46 is omitted in Fig. 1 of the drawings, for the sake of clearness, and a clearance is shown in Fig. 4 between the top of the cap 44 and the underside of the flange 45 for the same reason.

Turning the cap 44 in one direction will raise the bushing 39 and turning the cap 44 in the opposite direction will lower the same without turning it in the opening 40 of the flange 41 when the thread is omitted therein.

Means may be provided to keep the bushing 39 from rotating when the cap 44 is turned for raising or lowering said bushing.

The bulbs 23 at the lower ends of the tubes 24 pass through bushings 49 which are heat insulated interiorly as at 50 in Fig. 4 and threaded exteriorly as at 51 in Fig. 4 in engagement with threaded openings in the flange 33 of the strip 33—33a. The bushings 49 serve to prevent leakage of air into the housing 11 and duct 18.

The upper ends 52 of the bushing 49 may be prismatic to facilitate turning of the same.

The lower ends 53 of the bushings 49 are shown as tapered, to fit the bevelled seats of the openings 22 in the top of the duct 18.

The bushings 49 are shown in Figs. 4 and 5 as passing through openings 54 in the plate 14 and contacting the said seats 22.

The taper at the ends of the bushings 49 serves to bring the openings in the plate 14 into alignment with the openings 22 in the duct 18; they

also serve as valves for closing the said openings 22.

The bolts 34 which connect the flange 33 to the plate 14 fit loosely in the bolt holes of said plate to permit the alignment of the bushings 49 and the openings 54 in the plate 14 with the openings in the flange 33, and the bolt holes in the plate 14 for the bolts 16 permit the alignment of the bushings 49 with the said openings 22 by means of the said tapered ends 53.

The radiation shields 32 have at their front ends curved screens 55 one on the outer side of each of said tubes 24 for excluding the light from these directions, whereby to make the markings on the thermometer tubes more conspicuous.

The shields 32 also have at their rear ends stiffening ribs 56 which are integral with said shields 32.

A loop-shaped hanger 57 is shown in Fig. 1 as pivotally connected at its inwardly extending horizontal ends to lugs 58 on the flanges 41 of the strip 42.

The hanger 57 terminates at the upper end thereof in a hook 59 for suspending the psychrometer thereby.

In the modification of my psychrometer which is shown in Figs. 6, 7, 8 and 9 two compartments 60 and 61 of the housing are employed; each of these is semicylindrical in outline; the walls 62 and 63 respectively of the compartments 60 and 61 are joined to each other by means of flanges 64 thereon which extend inwardly, and suitable fastenings which are not shown.

A wall or partition 65 of heat insulating material is placed between the flanges 64 and extends from the joint top plate 14 to the joint bottom plate 13 of the compartments 60 and 61; bolts 16 are employed to hold the plates 13 and 14 together against the upper and lower edges of the walls 62 and 63.

A fan casing 66 is located in the compartment 60 and part of the wall 65 is employed as one of its sides; the casing 66 discharges into the compartment 60 air which is drawn into it by means of a fan 26 on a shaft 27 which is driven by a motor 28; the shaft 27 is shown as supported at the outer end thereof by an outboard bearing 67.

Atmospheric air is drawn into the casing 66 through a composite duct 18-68 which consists of an inner duct 18 and an outer duct 68 encompassing the same; frames 69-72 and 70-74 are employed to support the ends of the ducts 18 and 68.

The duct 68 has thereon a covering 71 of heat insulating material.

Curved flanges 72 on the frame 69-72 serve to connect the same to the front of the wall 63 with a layer of heat insulating material 73 therebetween.

Flanges 74 on the frame 70-74 serve to connect the same to the partition 65.

Each of the frames 69-72 and 70-74 has thereon an inner rectangular hub 75 for receiving therein the ends of the duct 18; the hubs 75 are joined to the frames 69-72 and 70-74 by means of bridge bars 77 which are integral with the said hubs 75 and with the frame 69-72 and 70-74. Air spaces or passages 76 extend between the duct 18 in the hubs 75 and the duct 68 which is supported at its ends in the hub 69 of the frame 69-72 and the hub 70 of the frame 70-74.

Air which is discharged from the fan casing 66 escapes from the housing 60 through openings 15, thereby ventilating the motor 28, the transformer 29 and the rectifiers 30 with their aux-

iliaries, whereby radiation of heat from these to the bulbs 23 is reduced or eliminated.

The other parts of the psychrometer in the herein described second modification are identical with or similar to the corresponding parts of the first modification above described and are similarly numbered or omitted in Figs. 6, 7, 8 and 9.

However, the bushings 79 in Figs. 8 and 9 are longer than the bushings 49 in Figs. 4 and 5, and they pass through openings 78 in the duct 68 in addition to the openings 54 in the plate 14.

Variations are possible and parts of my invention may be used without other parts.

I do not, therefore, restrict myself to the details as shown in the drawings.

I claim as my invention and desire to secure by Letters Patent:

1. A psychrometer comprising a pair of thermometer tubes, an air duct into which the bulbs of said tubes extend, another air duct encompassing the first mentioned air duct and having therein openings for the ends of said tubes to extend therethrough, the walls of the two ducts being spaced from each other, each duct being open to the atmosphere at one end thereof for the admission of air therethrough, a fan for circulating air through the ducts, a motor for driving the fan, a housing, having therein openings in registration with the openings in the outer duct, for the ends of said tubes to extend therethrough, encompassing the ducts and enclosing the motor with the fan, which is disposed to exhaust the air from the other end of each of said ducts into the housing, the end of each duct open to the atmosphere extending to an opening in the wall of said housing and the latter being provided with an egress for the exhaust air to the atmosphere.

2. A psychrometer comprising a pair of thermometer tubes, an air duct into which the bulbs of the thermometer tubes extend, the duct being open to the atmosphere at one end thereof for the admission of air therethrough, a fan for circulating air through the duct, a motor for driving the fan, a housing having therein openings for the ends of said tubes to extend therethrough, encompassing the duct and enclosing the motor with the fan, which is disposed to exhaust the air from the other end of the duct into the housing, the end of the duct open to the atmosphere extending to an opening in the wall of said housing and the latter being provided with an egress for air to the atmosphere and a partition of insulating material in said housing extending from side to side and from top to bottom of the housing, the said duct being located on one side of the partition and the motor being located on the other side thereof, the said partition having therein an opening for the said other end of the duct to communicate with the housing therethrough, whereby to prevent radiation of heat from the motor and its auxiliaries to the bulbs of the thermometers.

3. A psychrometer comprising a pair of thermometer tubes, an air duct into which the bulbs of said tubes extend, the duct being open to the atmosphere at one end thereof for the admission of air therethrough, a fan for circulating air through the duct, a motor for driving the fan, a housing, having therein openings for the ends of said tubes to extend therethrough, encompassing the duct and enclosing the motor with the fan, which is disposed to exhaust the air from the other end of the duct into the housing, and the latter being provided with an egress for the

exhaust air to the atmosphere; a flanged frame, for holding one end of the air duct in position, having its flanges secured to the wall of the housing at an opening in said wall, which is in line with said duct, and a gasket of insulating material placed between said flanges and the contiguous part of the wall of housing, whereby to prevent conduction and radiation of heat from the wall of the housing to the air duct through the said frame.

4. A psychrometer comprising a pair of thermometer tubes, an air duct into which the bulbs of the thermometer tubes extend, said duct being open to the atmosphere at one end thereof for the admission of air therethrough, a fan for circulating air through the duct, a motor for driving the fan, a transformer and a rectifier for said motor, a means for encompassing the said duct and for enclosing the said motor with said fan, said transformer and said rectifier, said encompassing and enclosing means having therein openings for the ends of said tubes to extend therethrough, said fan being disposed to exhaust the air from the other end of said duct into the enclosing means, the end of the duct open to the atmosphere extending to an opening in the wall of the said enclosing means and the latter being provided with a restricted egress for the exhaust air to the atmosphere, thereby diffusing the air in the enclosing means, thereby cooling the motor, the transformer and the rectifier and thereby reducing the radiation of heat from these to the said tubes.

5. A psychrometer comprising a pair of vertically disposed thermometer tubes, a horizontal air duct into which the bulbs of the thermometer tubes extend, the said air duct being open to the atmosphere at one end thereof for the admission of air therethrough, a fan for circulating air through the duct, a motor driving the fan, a housing, having therein openings for the ends of said tubes to extend therethrough, encompassing said duct and enclosing the motor with the fan, which is disposed to exhaust the air from the other end of the duct into the housing, the end of the duct open to the atmosphere extending to an opening in the wall of said housing and the latter being provided with an egress for the exhaust air to the atmosphere, radiation shields on the housing, to serve also as standards for supporting thereon the upper ends of the thermometer tubes, and means on said shields for raising and lowering said tubes, thereby varying and adjusting the vertical position of the bulbs at the lower ends of said tubes.

6. A psychrometer comprising a pair of vertically disposed thermometer tubes, a horizontal air duct into which the bulbs of the thermometer tubes extend, the said air duct being open to the atmosphere at one end thereof for the admission of air therethrough, a fan for circulating air through the duct, a motor for driving the fan, a housing, having therein openings for the ends of said tubes to extend therethrough, encompassing the duct and enclosing the motor with the fan, which is disposed to exhaust the air from the other end of said duct into the said housing, the end of the duct open to the atmosphere extending to an opening in the wall of the said housing and the latter being provided with an egress for the exhaust air to the atmosphere, radiation shields on the housing for said tubes, to serve also for supporting the upper ends of the tubes, and screens on the forward ends of the shields integral therewith, for excluding light from the sides of

the thermometer tubes, whereby to make the markings on said tubes and the mercury column contained therein more conspicuous.

7. A psychrometer comprising a pair of thermometer tubes, an air duct into which the bulbs of the thermometer tubes extend, the said duct being open to the atmosphere at one end thereof for the admission of air therethrough, a fan for circulating air through the duct, a motor for driving the fan, a housing, having therein openings for the ends of said tubes to extend therethrough, encompassing the duct and enclosing the motor with the fan, which is disposed to exhaust the air from the other end of the duct to the said housing, the end of the duct open to the atmosphere extending to an opening in the wall of the said housing and the latter being provided with a restricted egress for the exhaust air to the atmosphere, thereby diffusing the exhaust air in the housing and thereby effectively cooling the motor and reducing the radiation of heat from the same to the bulbs of the thermometer tubes.

8. A psychrometer comprising a pair of thermometer tubes, an air duct into which the bulbs of the thermometer tubes extend, said duct being open to the atmosphere at one end thereof, for the admission of air therethrough, a fan for circulating air through the duct, a motor for driving the fan, a housing, having therein openings for the ends of said tubes to extend therethrough, encompassing the said duct and enclosing the said motor with the fan, which is disposed to exhaust the air from the other end of the duct into the housing, the end of the duct open to the atmosphere extending to an opening in the wall of the said housing and the latter being provided with relatively small openings for discharging the exhaust air therethrough to the atmosphere, thereby cooling the motor; and thereby reducing the radiation of heat to said bulbs.

9. A psychrometer comprising a pair of thermometer tubes, a horizontal air duct into which the bulbs of the said tubes extend, the said air duct being open to the atmosphere at one end thereof for the admission of air therethrough, a fan for circulating air through the duct, a motor for driving the fan, a housing, having therein openings for the ends of said tubes to extend therethrough, encompassing the said duct and enclosing the motor with the fan, which is disposed to exhaust the air from the other end of the duct into the housing, the end of the duct open to the atmosphere extending to an opening in the wall of the housing, and the latter being provided with an egress for the exhaust air to the atmosphere, the housing including a top plate secured by means of long bolts which are adapted to be yieldable laterally, said top plate being thereby laterally adjustable, said duct having therein openings for the lower ends of the thermometer tubes to extend therethrough, bushings for closing the openings encompassing the lower ends of the tubes, said top plate having therein openings for the bushings to pass therethrough, the openings in said ducts being provided with bevelled seats and said bushings having tapered ends to fit said seats, whereby to bring said seats and said ends into alignment with each other and thereby to adjust the lateral position of the top plate with relation to that of the duct in a way to make the openings in the top plate coaxial with the openings in the duct.

10. The psychrometer described in claim 9, said bushings being heat insulated on the inner surfaces thereof, whereby to reduce radiation of

heat from the bushings to the thermometer tubes.

11. The psychrometer described in claim 1, a partition of insulating material in said housing extending from side to side and from top to bottom of the housing, the said ducts being located on one side of the partition and the motor being located on the other side thereof, the said partition having therein an opening for the said other ends of the ducts to communicate with the housing therethrough, a pair of frames for spacing the walls of the ducts from each other and for holding the ends of the ducts in position, each frame having thereon a hub for the end of each of said ducts, said hubs on each frame being connected to each other by suitable bridge bars, one of said frames being connected to the said housing and the other frame being connected to the said partition.
